UNITED STATES PATENT OFFICE.

CLAUDE F. FOWLER, OF BUFFALO, NEW YORK.

KEY GUARD.

Application filed March 13, 1922. Serial No. 543,184.

To all whom it may concern:

Be it known that I, CLAUDE F. FOWLER, a citizen of the United States, residing at Buffalo, in the county of Erie and State of New York, have invented certain new and useful Improvements in Key Guards, of which the following is a specification.

My invention relates to a key guard or fastener, and it has for its object the provision of a guard which can be attached to any ordinary door without boring holes or otherwise providing special means on or in the door for fastening the guard thereto.

Another object of my invention is the provision of a key guard which can be applied to the ordinary escutcheon at the inner side of a door, and which will so fasten a key that it cannot be turned within the key hole of the door to bring the barb there- 20 of in line with the elongated lower portion of the key hole, which would permit the key to be forced from the key hole from the outside of the door and allow a duplicate or skeleton key, or a lock-picking tool to be inserted into the key hole for unlocking the lock.

A further object of my invention is the provision of a guard for the purpose stated, which is of simple construction, comparatively inexpensive, and which can be retained on a door, or carried on one's person for convenience when traveling and it is desired to have the protection this guard will furnish for sleeping quarters in hotels 35 and other places.

The invention consists in the novel features of construction and in the arrangement and combination of parts to be hereinafter described and more particularly 40 pointed out in the subjoined claims.

In the drawings:—

Fig. 1 is an elevation of a portion of a door having my improved guard applied to the escutcheon at one side thereof.

Fig. 2 is a section taken on line 2—2, Fig. 1.

Fig. 3 is a detached perspective view of the guard viewed from the front.

Fig. 4 is a detached perspective view of the guard viewed from the rear.

Fig. 5 is a horizontal section taken on line 5—5, Fig. 1.

Fig. 6 is a rear view of the upper portion of the guard.

Referring to the drawing in detail, the numeral 6 designates the door, mortised as

at 7, to receive the usual lock 8, shown in Figs. 2 and 5, the locking mechanism within the lock-casing being, however, omitted. Opposite walls of this lock have alined key 60 openings 9, and the door at opposite sides of the lock-receiving mortise is provided with key openings 10.

As is the custom, each side of the door has an escutcheon 11 applied thereto, and these 65 escutcheons have key openings 12 alined with the key openings 9 and 10. The several key openings in the parts referred to may be said to constitute the key hole of the door in which a key 13 is to be inserted 70 either from the outer side of the door or the inner side.

In the drawing I have shown the key inserted into the key hole from the inner side of the door, and the removal thereof from 75 the outer side is to be prevented by my improved guard, to be presently described.

The key is shown positioned with its barb 14 at right angles to the length of the key hole, or in a horizontal position; and therefore withdrawal of the key cannot take place until it is given a one-quarter turn either to the right or left to bring the barb into vertical or depending position in line with the lower portions of the key openings 80 9, 10 and 11 formed, respectively, in the lock, door and escutcheon.

Keys of the type shown are usually provided with flat shanks 15, and my improved guard is adapted for use in connection with 90 a key having such a shank. The guard includes a key-engaging member in the form of a flat plate 16 tapered at opposite ends, but if desired, the plate may be given any other formation.

This plate is provided with a key slot 17, which is arranged transversely near the upper end thereof and opens at one edge of the plate, as at 18. The outer portion of the plate is narrowed to form a shoulder or key 100 stop 19, and the plate is provided with an inwardly-directed lip 20 at the inner end of the key slot 17.

Arranged centrally in the plate beneath the key slot 17 is a vertically-disposed opening 21 which is slightly enlarged downwardly from its upper end. This opening is adapted to be alined with the opening 12 in the escutcheon at the inner side of the door.

22 designates a narrow retainer member 110 formed of a strip of metal applied to the outer face of the plate 16 and having its

upper end bent inwardly through the opening 21 in said plate, as at 23, and thence downwardly, as at 24, to form a hook, the downwardly-bent portion being spaced from the rear surface of the plate a distance approximately equaling the thickness of the escutcheon at the inner side of the door. The lower end of the metallic strip forming the retainer member is preferably bent outwardly, as at 25, to form a finger grip by means of which the retainer member may be conveniently slid upwardly or downwardly on the plate 16. For this purpose the retainer member has a vertically-disposed slot 26 formed therein through which a thumb screw 27 is passed that is threaded into the plate 16, the head of the thumb screw being adapted to engage the outer surface of the retainer member in any position it may be placed.

The plate 16 is provided on its inner side at the bottom of the vertical opening 21 with two inwardly extending ears 28. These ears lie on opposite sides of the hook portion at the upper end of the retainer member 22 or, in other words, at opposite sides of the opening 21.

The plate 16 is provided on its inner surface, between the key slot 17 and the opening 20, with an inward projection 29 providing beveled surfaces 31 at the opposite sides of a downwardly inclined ridge 32 extending from the key slot 17 to the upper end of the opening 21, the beveled surfaces 31 at opposite sides of the ridge 32 tapering downwardly from said slot to a point common to both and to the ridge 32.

When applying the guard to a door, it is simply necessary to position the key so that the shank 15 will be horizontal. The guard is then placed over the shank of the key by sliding it sidewise to enter the shank in the key slot 17. This may be done while having the guard positioned a slight distance from the escutcheon at the inner side of the door. The retainer member 22 is then elevated on the plate 16, if not already elevated, and the guard moved toward the escutcheon to enter the hook portion at the upper end of said retainer member through the key opening 11 in said escutcheon. By then lowering the retainer member 22 the hook portion 24 will engage behind the escutcheon, as shown in Fig. 2, and when the thumb nut 27 is tightened the hook-shaped upper end of the retainer member will be firmly clamped to said escutcheon, with the result that the entire guard will be retained in position on the door.

It is to be noted that the opening 21 in the plate 16 will be alined with the key hole in the door, with the result that any tool or object forced through the key hole will also pass through the opening 21, making it practically impossible to force the guard from

the escutcheon, with a view of disengaging it from the key.

It is also to be noted that the ears 28 at opposite sides of the hook-shaped upper end of the retainer member serve to prevent a tool being worked underneath the inwardly bent portion 23 of said retainer member, with a view of forcing the same upwardly and disengaging the guard from the escutcheon. The inwardly-directed lip 20 also prevents a tool being forced underneath the shank of the key from the outside of the door with a view of forcing the key over the shoulder 18 in the key slot, or with a view of forcing the key guard laterally to loosen the hold of the retainer member from the escutcheon.

The inward projection 29, or ridge as it may be termed, provides inclined surfaces which practically occupy a space at least equaling the full width of the key hole in the lock and therefore any attempt to insert a tool, nail, or other article through the key hole of the door with a view of placing the end thereof against the guard and hammering or otherwise forcing the guard from the escutcheon, will be prevented, since such a tool would be caused to slide down the inclined ridge 32 of the inclined surface 31 at opposite sides of the ridge.

The guard shown and described is believed to prevent forcible removal of the same from the escutcheon from the outer side of the door by any means open to a person accustomed to manipulating locks with a view of gaining surreptitious entrance to a room.

Having thus described my invention, what I claim is:

1. A key guard comprising a flat key-engaging member having a key slot extending inwardly from one edge and a shoulder in said key slot between which and the inner end of said slot the shank of a key is adapted to be retained, and means on said key-engaging member for connection with the escutcheon of a door for retaining said key-engaging member in engagement with the shank of a key in the door.

2. A key guard comprising an elongated key-engaging member having an opening therein, a retainer member vertically adjustable on said key-engaging member and having a hook portion extending through said opening and adapted for engagement with the escutcheon of a door at the lower end of the key-opening therein.

3. A key guard comprising a key-engaging member in the form of a plate having a transverse key slot and an opening in said key-engaging member beneath said key slot, and a retainer member applied to the outer side of said key-engaging member and having a hook portion extending through said opening and adapted to engage the escutcheon.

of a door at the lower end of the key opening therein.

4. A key guard comprising an elongated member having a transverse key slot therein

5 and a vertically-disposed opening spaced from said key slot, a vertically-disposed retainer member having a slot therein, a hook at one end extending through said vertically-disposed opening and a finger grip at 10 the other end, and a thumb screw extending through said slot and threaded into said elongated member.

5. A key guard comprising an elongated plate having a key slot near its upper end 15 opening at one edge thereof and adapted to receive the shank of a key in a door, an inwardly-directed lip at the inner end of said key slot and a vertically-disposed opening beneath said key slot having inwardly-bent ears at the lower end thereof, and a retainer member adjustable on said elongated plate and having a hook at its upper end extending through said opening and adapted to engage the escutcheon of the 20 door at the lower end of the key opening therein, said hook being positioned between said inwardly-bent ears at the lower end of said opening.

6. A key guard comprising an elongated 30 plate having a transverse key slot opening at one edge thereof and provided with a narrowed outer end forming a shoulder in opposition to the inner end wall of said key slot and an inwardly-directed lip at the inner end of said key slot, and means for retaining said plate on a door with the shank of a key positioned between the inner end of said key slot and the shoulder therein.

40 7. A key guard comprising an elongated plate having a transverse key slot opening at one edge thereof, a vertically-disposed opening beneath said key slot adapted to be aligned with a key opening in the escutcheon 45 of a door and an inward projection on the inner side of said plate between said open-

ing and key slot having an inclined surface, and a retainer member on said plate having a hook-shaped end extending through said opening.

50

8. A key guard comprising an elongated plate having a transverse key slot opening at one edge thereof, a vertically-disposed opening beneath said key slot adapted to be aligned with a key opening in the escutcheon 55 of a door and an inward projection on the inner side of said plate between said opening and key slot having inclined surfaces, and means for attaching said elongated plate to a door.

60

9. A key guard comprising an elongated plate having a transverse key slot opening at one edge thereof, a vertically-disposed opening beneath said key slot adapted to be aligned with a key opening in the escutcheon 65 of a door and an inward projection on the inner side of said plate extending from said key slot to said opening and having a downwardly inclined ridge and opposite inclined surfaces tapered to a common point, and 70 means adjustable on said elongated plate for retaining said plate on the door.

70

10. A key guard comprising an elongated plate having a transverse key slot opening at one edge of said plate and an opening 75 beneath said key slot adapted to be aligned with the key opening in an escutcheon of a door, tool deflecting means on said plate between said slot and said opening, and means adjustable on said plate for detachably engaging said escutcheon.

80

11. A key guard comprising a key engaging member having an opening therein, a retainer member provided with a hook extending through said opening and adapted 85 to engage an escutcheon of a door at the lower end of the key opening therein, and means on said plate to prevent the insertion of a tool underneath said hook from the outer side of the door.

90

In testimony whereof I affix my signature.

CLAUDE F. FOWLER.
